1 Claim

ABSTRACT OF THE DISCLOSURE

A device for providing the operator of a garment press with a cool air environment by directing a continuous stream of relatively cool, steam chasing air in front of the press, the device comprising a blower mounted near the base of the press which draws relatively cool air in and pushes it upwardly through a conduit supported by the press table. At the upper end of the conduit, the air exits through a movable nozzle that directs it generally in the vicinity of the head of the press operator.

This invention relates generally to garment pressing apparatus, and more particularly it relates to a combined safety and ventilating system for use in combination with a conventional garment pressing machine for protecting the press operator from steam and radiant heat, by providing him with a continuous flow of cool air.

In a conventional garment pressing machine, the garment is subjected to steam in order to soften the material before it is pressed by the pressing element. This preliminary steaming is usually accomplished by placing the garment on the lower pressing element, which is known as the buck; moving the upper pressing element, which is called the head, downward until it is adjacent to the garment; and injecting steam through apertures in the face of a pressing element onto the garment. The confined space between the head and the buck forms a channel which directs the released steam out of the pressing machine directly towards the operator. Also, when badly wrinkled cloth is given a preliminary buck steaming with steam from the buck while the head of the garment press is open, steam spouting upwards from the buck is deflected towards the operator. In addition to the continuous ejection of steam, the pressing element of the presser becomes extremely hot and the operator is constantly subjected to radiant heat from the pressing machine even during the intervals when the garment is not being steamed.

The subjection of the operator of a garment presser to steam and heat for protracted periods often produces serious physical difficulties, particularly those of a respiratory nature. Furthermore, the clouds of steam and radiant heat interfere with the operator's vision and greatly slow down his rate of work.

Although the aforesaid problem existed for many years in the garment pressing field no satisfactory solution was available prior to the present invention, and machines heretofore produced failed to provide any means for protecting the operator from steam and heat.

It is therefore a general object of the present invention to provide an improved ventilating system for a pressing machine and the like which will contribute materially to operator comfort, improved pressing quality, achieve cost reduction, and contribute materially to the safety of the operator. Another object of the present invention to provide a combined ventilating safety device for use on a pressing machine which provides a cool stream air around the press operator which continuously removes steam, heat, lint, and fumes.

In accordance with illustrative embodiments demonstrating objects and features of the present invention advantageously, a conduit means is provided which is attached to a suitable forced air creating device such as a

2

blower, for drawing in air from a relatively cool environment and directing it so as to push away heated air and steam from the space around but particularly in front of the operator. My invention utilizes the tendency of heated air to rise, and of cooler air to seek a lower level by locating the intake blower of my system in an area generally well below the table level of the press.

Still another object of my invention is to provide a cool air stream and steam chaser device that can be made either as an integral part of a garment pressing machine, or which can be manufactured as a portable device and attached to the presser machine. In either embodiment my device is light in weight, and the blower for creating an out-draft may be easily attached to the frame of the presser without requiring any structural changes on the machine. In a normal installation, the upper position of the conduit may be useful as a means for helping the operator in the manipulation of garments during pressing.

Further objects, features and advantages of the present invention, will be more fully appreciated by reference to the following detailed description of one embodiment of the present invention, taken in conjunction with the accompanying drawings, wherein:

FIG. 1 is a view in perspective of a typical garment pressing machine utilizing in combination therewith a ventilating system embodying the principles of my invention.

FIG. 2 is a front view showing a modified form of my device for use with two garment pressing machines.

Referring to the drawing, a ventilating device 10 embodying the principles of my invention is shown in FIG. 1 installed on a conventional garment pressing machine 12 of the type that may be found in almost any dry cleaning and pressing establishment. The garment pressing machine has a base support 14 for supporting the remainder of the machine and for housing the usual pressing level means and vacuum lines controlling the operation of the machine in response to foot pressure by the operator. A table 16 is supported on the base 14 and in turn the table supports a buck stand 18 and a buck 20 which is the stationary lower pressing element of the machine. A head 22 serves as the upper pressing element, and is mounted on a pressing level 24.

At the base support 14 of the pressing machine a blower 26 is mounted on a bracket 28 which may be fixed to the base support. The blower is driven by an electric motor and has an inlet end 30 which draws in surrounding air. In normal operation the blower runs at a constant speed that steadily draws in cool air.

Attached to the blower outlet is a conduit section 32 that extends upwardly through an aperture 34 in or around the end of the table 16. The upper portion of the conduit extends above the buck 18 and terminates near the front edge of the pressing machine roughly at the normal head level of the operator.

To the upper end of the conduit section 32 is connected an adjustable stack or outlet nozzle member 36 which can be adjusted upwardly or downwardly and/or rotated to any desired direction by the operator.

In a somewhat modified form of my invention, as shown in FIG. 2, a portable type of ventilating device 10a is shown which may be placed near or be connected to a garment pressing machine in some suitable manner. Essentially, the device includes the motor-blower unit 26a from which extends a conduit section 32a that may be self supporting or may be clamped to the garment presser table by any convenient clamping device. At the outlet end of the conduit section, I may provide a two-way outlet stack member 36a so that air may be blown in two directions simultaneously to relieve operators of two pressers side by side.

In operation, the blower 26 or 26a, being located near to floor draws in relatively cool air from around the lower part of the pressing machine through its intake. This air is forced upwardly through the conduit section end and emitted through the outlet member 36 in front of the operator's face working at the front edge of the press. This dissipates the steam while driving away and cooling the normally hot, humid air around the operator, thereby greatly increasing his efficiency and comfort.

To those skilled in the art to which this invention relates, many changes in construction and widely differing embodiments and applications of the invention will suggest themselves without departing from the spirit and scope of the invention. The disclosures and the description herein are purely illustrative and are not intended to be in any sense limiting.

I claim:

1. A garment pressing machine having a stationary buck mounted on a base and a movable upper pressing head, the head and buck having opposing faces, the head and buck having means for releasing steam through said faces, and an accessory comprising a driven blower positioned on the base of the machine adjacent the floor, a conduit secured to the outlet of said blower and extend-

ing upwardly therefrom to the upper region of the machine and supported thereon, adjustable means attached to the upper end of said conduit for directing cooling air from the blower away from the machine and generally in the vicinity of the operator's face, to provided a cool air environment.
